UNITED STATES PATENT OFFICE.

WILLIAM HAGUE ALLISON, OF MORRISBURG, CANADA.

BUOY.

SPECIFICATION forming part of Letters Patent No. 747,114, dated December 15, 1903.

Application filed April 10, 1903. Serial No. 152,032. (No model.)

To all whom it may concern:

Be it known that I, WILLIAM HAGUE ALLISON, of Morrisburg, in the Province of Ontario and Dominion of Canada, have invented 5 certain new and useful Improvements in Buoys; and I do hereby declare that the following is a full, clear, and exact description of the same.

My invention relates particularly to gas- 10 buoys; and it has for its object to provide a special anchor connection whereby a buoy will be kept constantly in a vertical position however the velocity of the current may vary.

The invention may be said briefly to consist in furnishing the buoy with a bail fastened near the top of the body thereof, the usual anchor-chain or other ordinary anchor connection being fastened to the lower end of the buoy and said bail being, like the anchor-chain, connected to the anchor. For full 15 comprehension, however, of my invention reference must be had to the accompanying drawings, forming a part of this specification, in which like symbols indicate the same parts, 20 and wherein—

Figure 1 is a side elevation of a gas-buoy in a current of water and provided with my invention, and Fig. 2 is a plan view thereof.

The buoy *b* is in the main of ordinary construction, and other constructions than that illustrated may have my invention applied thereto to advantage. The anchor *c* is also of ordinary construction.

The anchor-chain *d* is connected at one end 35 to the center of the under side of the buoy and at its other end to the anchor, and it is divided near its lower end and its divided ends connected together by a swivel *e*. I connect a bail *j* at one end to the upper portion 40 of the buoy and at its other end to the anchor-chain just above the swivel, as at *f*. This bail may be connected either to a pair of rings *h*, secured to the top of the buoy-body, or to a pair of lugs *i*, formed in one with the 45 band *k*, encircling the body of the buoy and adjustable vertically thereon. In either case the bail will be connected to the anchor-chain either by a length constituting a part

of that from which the bail is made or a separate length of wire rope or chain connected 50 to the bail when the latter is required to be of greater strength.

My object in providing the movable band is to enable the point at which the bail is fastened to be adjusted higher or lower upon 55 the buoy, according to the speed of the current, while if a current of exceeding strength is to be buoyed I utilize both the ring-connected bail at the top of the buoy and the band connection slightly above the middle 60 thereof. If desired, the band alone may be used with a connection therebetween and the anchor and the chain connection to the under side of the buoy and the branch connection to the top thereof dispensed with without 65 departing from the spirit of my invention.

What I claim is as follows:

1. The combination with a buoy, an anchor-fastening connected to the lower end thereof, and an auxiliary fastening leading from the 70 top thereof to said anchor-fastening substantially as described and for the purpose set forth.

2. The combination with a buoy, an anchor-fastening connected to the lower end thereof, 75 a bail, means for fastening said bail to the upper portion of said buoy, and a length of wire rope, chain, or the like connecting said bail to the anchor-fastening, substantially as described and for the purpose set forth. 80

3. The combination with a buoy, a movable band encircling said buoy, an anchor, and a connection between said band and said anchor, substantially as described and for the 85 purpose set forth.

4. The combination with a buoy, an anchor, a chain leading from said anchor to the under side of said buoy, a pair of rings fastened to the top of the body of said buoy at different circumferential positions, a branched 90 fastener connected at the ends of its branches to said rings and at its opposite end to the anchor-chain, substantially as described and for the purpose set forth.

5. The combination with a buoy, an anchor, 95 and a chain connecting said anchor to the un-

der side of said buoy, of a band encircling the body of said buoy, and having a pair of lugs at diametrically opposite sides thereof, a bail connected at its ends to said lugs, and a connecting length leading from said bail to said anchor-chain, substantially as described and for the purpose set forth.

In testimony whereof I have affixed my signature in presence of two witnesses.

WILLIAM HAGUE ALLISON.
